OIL BURNER

Filed Dec. 17, 1927

2 Sheets-Sheet 2

UNITED STATES PATENT OFFICE.

JOSEPH GRISON, OF NEWARK, NEW JERSEY.

OIL BURNER.

Application filed December 17, 1927. Serial No. 240,690.

This invention relates to oil burners and more particularly to that type of oil burner used for heating dwellings, and the like.

Oil burners now in use for the heating of houses, etc. are generally of the automatic type and require a number of accessories such as thermostats, electric motors, blowers, etc. with the result that the cost of installing an automatic oil burner is prohibitive to persons of moderate means.

It is an object of my invention to provide an oil burner which will satisfactorily heat dwellings not exceeding eight rooms, and which may be cheaply made so that the total cost of installing a complete oil burner will be within the means of all. Also my burner is so constructed that the fuel consumption will be moderate, and the cost of upkeep negligible.

A further object is to provide a burner having a surface over which oil fed by gravity may flow, the surface being so shaped as to prevent the oil from collecting in spots, and the accumulating of carbon deposits on the burner due to incomplete combustion of the oil.

A further object is to provide means for super-heating air supplied to the burner so that the oil will be heated to a gaseous state by the air.

These and other objects are attained by the novel construction combination and arrangement of parts hereinafter described and shown in the accompanying drawing, constituting a material part of this disclosure, and in which:

Figure 1 is an elevational view of an oil burning system.

Figure 2 is a cross-sectional side view of the improved burner.

Figure 3 is a plan view of the air heating chamber used with the burner.

Figure 4 is a plan view of the burner.

Referring to the drawings, my burner is shown consisting of a bowl shaped member 3, having a plurality of radial extensions 4, which are provided with flanges 5 to enable the burner to be mounted by suitable means on the grate 2, of a furnace.

In the center of the member 3 is an integral upstanding hollow conical projection 6, which terminates in a spherical cap 7, the latter being apertured at 9 to accommodate the pipe 10, through which oil may be fed by gravity.

A plurality of apertures 8 are provided in

the sides of the member 3 to enable the passage of air and burned gases therethrough.

In the bottom of the member 3, an aperture 17 accommodates a drain pipe 18, which leads to an automatic cut-off device 19, the latter being of standard design. Should for any reason, the flame be extinguished, the oil will, of course, continue to flow through pipe 10, over the spherical cap 7 and fall into the bottom of member 3, from whence it will be drained off through pipe 18 until it reaches the automatic cut-off 19, which will then actuate a valve to stop the further flow of oil through pipe 10.

It will be noted that the extensions 4 are provided with apertures 20 and upstanding flanges 15 which facilitate the mounting of the air chamber 11, the latter having a plurality of hollow legs 12 adapted to fit over the apertures 20. The walls of the legs 12 are very thin and are corrugated or waved as at 13, so that the passage of air therethrough will be retarded, resulting in the super-heating of the air to such an extent that when such air passes through the opening 14 in the chamber 11, it will have attained a temperature sufficient to volatilize the oil which flows over the surface of cap 7. Such action, obviously, results in the burning of the oil in a gaseous state, and consequently, complete combustion with practically no carbon deposits.

The spherical shape of the cap 7, the surface of which is highly polished, prohibits the collecting of carbon deposits thereon, and also causes the oil exuding from pipe 10 to flow in a film over its surface.

In operation, a quantity of oil is first placed in the bottom of the member 3 and ignited by a pilot connected with a gas supply by the pipe 16, or the oil may be ignited by other means such as the burning of paper in the member 3. This initial burning of oil is sufficient to heat the cap 7 considerably and to ignite and cause the exuding oil to burn as it passes in a film over the spherical cap 7. While these initial operations are going on, the air in the legs 12 of chamber 11 is being heated to a high temperature, and within a few seconds the superheated air passing through the opening 14 will volatilize the oil exuding from pipe 10 resulting in the complete combustion of the oil and a tremendous heat for the purpose intended.

Normally, such a burner, designed to heat

a dwelling not exceeding 8 rooms, will not consume over one half gallon of oil per hour, and on mild days the flow of oil through pipe 10 may be controlled by a valve so that a smaller quantity of oil will be consumed each hour.

From the above description it will be seen that I have provided an efficient oil burning apparatus which may be manufactured and 10 installed at low cost, and yet satisfactorily heat dwellings with a minimum expenditure for fuels.

The foregoing disclosure is to be regarded as descriptive and illustrative only, and not 15 as restrictive or limitative of the invention, of which obviously an embodiment may be constructed including many modifications without departing from the general scope herein indicated and denoted by the appended 20 claims.

Having thus described my invention, what I claim as new and desire to secure by Letters Patent, is :

1. In an oil burning apparatus for heating 25 dwellings, a bowl-shaped member having radial extensions by which it may be mounted on a standard grate, said chamber having a plurality of apertures in its wall, an integral upstanding frusto-conical projection in the 30 center of said member, a polished spherical cap removably mounted on the projection, said cap having an aperture therethrough to

accommodate a pipe, upstanding flanges on said radial extensions, a hollow chamber having a plurality of legs adapted to be positioned on the member by means of said upstanding flanges, said extensions having apertures coinciding with the hollow legs; the walls of said hollow legs being very thin and corrugated to retard the passage of air 46 therethrough.

2. In an oil burning apparatus, a member having extensions by which it may be mounted on a grate, a frusto-conical projection in the center of said member, a polished spherical cap removably mounted on the projection, said cap having an aperture therethrough to accommodate a pipe, a hollow chamber having a plurality of hollow legs adapted to be mounted on said member to coincide with apertures therein, the walls of 50 said legs being corrugated to retard the passage of air therethrough.

3. In an oil burning apparatus, a member adapted to be mounted on a grate, a frusto-conical projection in the center of said member, a highly polished spherical cap removably mounted on the projection, and means 55 mounted on said member for superheating 60 air.

This specification signed this fifteenth day of December, 1927.

JOSEPH GRISON.
